United States Patent Office

Des. 194,290
Patented Dec. 25, 1962

194,290

JAR

Arnold J. Copeland, Weston, Conn., and Robert Baker, Hastings on Hudson, and Robert Y. Kimura, New York, N.Y., assignors to Standard Brands Incorporated, New York, N.Y., a corporation of Delaware

Filed Nov. 10, 1961, Ser. No. 67,470

Term of patent 14 years

(Cl. D58—25)

FIG. 1

FIG. 2

FIG. 3

FIG. 1 is a side elevational view of a jar embodying our new design;

FIG. 2 is an end elevational view thereof; and

FIG. 3 is a bottom plan view thereof.

The side and end not shown are substantially the same as the side and end shown.

We claim:

The ornamental design for a jar, as shown and described.
